JOINTED BRACKET

William A. Mendelsohn, Chicago, Ill., assignor to
 Burton Manufacturing Company, Chicago, Ill.,
 a corporation of Illinois

Application June 17, 1949, Serial No. 99,668

2 Claims. (Cl. 248—292)

1

This invention relates in general to certain new and useful improvements in jointed brackets and, more particularly, a joined bracket having a counter-balanced swivel.

The principal object of the present invention is to provide tension means for counter-balancing the gravitational force of swingable members, as in lamps supporting arms or brackets, and the like, in order to permit movement of the members under very slight pressure, and at the same time maintain the members securely and firmly in any position to which they have been moved.

A further object of the present invention is to provide tension means for counter-balancing swingable members, which means may be regulated to provide varying degrees of tension, and is hence easily adapted for a marked variety of uses.

An additional object of the present invention is to provide tension means for counter-balancing swingable members which is reliable in operation and is economical in construction.

With the above and other objects in view, my invention resides in the novel features of form, construction, arrangement, and combination of parts presently described and pointed out in the claims.

In the accompanying drawing—

Figure 1 is a fragmentary perspective view of an adjustable counter-balanced bracket constructed in accordance with and embodying the present invention and adapted for use as a lamp standard;

Figure 2 is a vertical sectional view of the swivel joint;

Figures 3 and 4 are transverse sectional views taken along lines 3—3, 4—4, respectively, of Figure 2;

Figure 5 is a transverse sectional view taken along line 5—5 of Figure 3; and

Figure 6 is a transverse sectional view taken along line 6—6 of Figure 2.

Broadly speaking, the present invention resides in providing a jointed supporting bracket comprising two arms swingably connected by a joint having self-contained counter-balancing means whereby the jointed arms may be moved by slight or finger tip pressure into a selected position, and be maintained securely at any position at which movement is stopped.

Referring now in more detail and by reference characters to the accompanying drawing which illustrates a preferred embodiment of the present invention, A designates a supporting bracket comprising two arms 1, 2, pivotally connected

2

by a rocking joint 3. At its outer end the arm 2 is bifurcated and provided with a conventional swivel 4 for supporting a vertical leg 1 provided at its upper end with a lamp B. The arm 1 is of general rectangular cross section having front and back walls 5, 5', and side walls 6, 6', and being open at its lower end for receiving the reduced upper end 1 of a connecting member 8 to which it is secured by screws 9 extending through suitable apertures in the walls 5', 6, 6'.

The connecting member 8 is provided with an internally threaded collar portion 10 for suitable attachment to a conventional floor standard s. At their upper ends the side walls 6, 6', of the arm 1 project forwardly beyond the plane of the front wall 5' in the formation of somewhat semi-circular joint leaves 11 provided with axially aligned concentric apertures 12, the rearward portions of which are peripherally enlarged to form cam slots 13. The upper transverse margin 15 of the front wall 5 is located just below the point of intersection between the arcuate margin of the leaves 11 and the forward vertical margin of the side wall 6 and the back wall 5' at its upper end is curved upwardly and forwardly along the rearwardly presented portion of the arcuate margins of the leaves 11, terminating substantially above the upper margin of the front wall 5 in the provision of an opening 14 between the arcuate portions of the side walls 6, 6', and the top and forward margins of the walls 5, 5', respectively.

Provided within the arm 1 and extending transversely thereacross is a swivel block 15 supported at its ends by shoulder screws 16 which project through suitable apertures in the sides 6, 6'. Centrally provided in the swivel block 15 is a vertical passage 17 for slidable projection therethrough of an elongated screw member 18 which extends slidably through a bore 19 in a spring retainer member 20 disposed beneath the block 15 and having a diametrically reduced lower portion in the provision of an abutment shoulder 21, against which bears the upper end of a compression spring 22. At its lower end the compression spring 22 bears against the shoulder 23 of a second spring retainer member 24 of similar construction to the member 20 but having a central bore 25 internally threaded for engagement with the threaded lower end 26 of the tension screw 18. The upper end of the screw 18 is formed in the provision of an eyelet 27 through which transversely extends a stop pin 28, the ends of which project through the cam slots 13 of the apertures 12, respectively. The arm 2, like the arm

1, is rectangular in cross section having a top wall 29, a bottom wall 30, and side walls 31, which are provided at their rearward ends with substantially circular joint leaves 32 spaced apart in such a manner as to snugly overlie and abut facewise against the leaves 11, and are provided with radially inwardly extending arcuate recesses 33 for embracingly fitting around and engaging the stop pin 28. Forwardly of said recesses 33 the leaves 32 are respectively provided with apertures 34, concentrically aligned with the apertures 12 of the leaves 11.

Positioned in facewise abutment against the outer faces of the leaves 11 are cover-bearings 35, 36. The cover-bearing 35 is provided with a central aperture 37 concentrically aligned with the apertures 12 and the apertures 34 and a concentric boss 37' adapted to fit snugly within and ride peripherally against the margins of the aperture 12. The bearing 36 is integrally provided with a stem 38 projecting inwardly and concentrically through said aligned apertures 12, 34, into the aperture 37 the bearing 35 is also provided with a circular boss 38' adapted to fit snugly within, and ride peripherally against, the margins of the other aperture 12. At its outer end the stem 38 is axially drilled and tapped for receiving a screw 39 having a flared head 39', which is seated in a countersunk enlargement 40 at the outer end of the aperture 37.

Encircling the stem 38 and bearing at its end against the inner faces of the end portions of the joint leaves 32 is a spacing sleeve member 41. The cover-bearings 35, 36, are provided on their inner faces with axially aligned recesses 42, 43, respectively, for receiving the ends of the stop pin 28. Disposed between the joint leaves 11, 32, respectively, are phosphor bronze washers 44, 45, respectively, and suitably wedged in circular recesses 46, 47, provided in the inner faces of the cover-bearings 35, 36, respectively, and concentric with the stem 38, are annular felt wicks 48, 49. Extending through rubber insulating ferrule 50 mounted in the rear wall 51 is a pair of wires 51 which lead from a source of electricity (not shown) and extend across the upper end of the arm and down through the arm 2 for conducting electricity to the lamp B.

In operation it will be seen that downward tilting movement may be imparted to the adjusting arm 2 by exercising slight pressure which lifts the stop pin 28 to cause the stem member 18 to be carried upwardly through the passage 19 of the member 20 and the bore 17 of the swivel block 15, bringing the retainer member 24 therealong to effect compression of the spring 22. Thus it will be seen that any gravitational effect upon the arm 2 will be counter-balanced by the spring 22 whereupon the arm 2 will remain fixed in the selected position. Conversely, if the arm 2 is swung upwardly the stop pin 28 will be carried downwardly and the spring 22 will expand exerting a substantial lifting force so that only very light manual pressure is required. Since the joint leaves 11 are stationary, the cam slots 13 therein, by restraining engagement with the stop pin 28, serve to limit the arc through which

the arm 2 may be moved. Thus, when the stop pin 28 is in contact with the lower end of the cam slots 13 the upper limit of movement of the arm 2 will have been reached, and, correspondingly, the upper end of the cam slots 13 determine the extent of downward movement of the arm 3.

Adjustment may be made by threading the retainer member 24 upwardly or downwardly along the end 26 of the screw 18 in order to regulate the resisting force of the spring 22 so that it will be just a slight bit less than enough to overcome the friction between the leaves 11, 32, under the particular load resulting from the weight of the arm 2 and the lamp B carried thereby.

It should be understood that changes and modifications in the form, construction, arrangement and combination of the several parts of the jointed brackets may be made and substituted for those herein shown and described without departing from the nature and principle of my invention.

Having thus described my invention what I claim and desire to secure by Letters Patent is:

1. A jointed bracket comprising a first arm, a second arm, said arms being rectangular in cross section with the central portion hollow, joint leaves provided on one end of each of said first and second arms, bearing members engaging said joint leaves of the first and second arms for pivotally securing said arms, an elongated screw swivelly mounted in said first arm and integrally provided at its upper end with a tubular eye, spring means associated with said screw, and a pin rotatably extending through said tubular eye and inserted at its ends in the joint leaves for swingably connecting said screw to the joint leaves of the first and second arms.

2. A jointed bracket comprising a first arm, a second arm, said arms being rectangular in cross section with the central portion hollow, joint leaves provided on one end of each of said first and second arms and having aligned slots in their extremities, bearing members engaging said joint leaves of the first and second arms for pivotally securing said arms, an elongated screw swivelly mounted in said first arm and integrally provided at its upper end with a tubular eye, shoulder-providing members mounted spacedly on said screw, a spring encircling said screw and bearing at its ends against the shoulder-providing members, a pin rotatably extending through said tubular eye and inserted at its ends through the aligned slots in the first and second arms.

WILLIAM A. MENDELSON.
